UNITED STATES PATENT OFFICE.

CHARLES KOCHER, OF KENOSHA, WISCONSIN.

AMUSEMENT APPARATUS.

Application filed October 31, 1924. Serial No. 747,025.

To all whom it may concern:

Be it known that J. CHARLES KOCHER, a citizen of the United States, and resident of Kenosha, in the county of Kenosha and State of Wisconsin, have invented certain new and useful Improvements in Amusement Apparatus; and I do hereby declare that the following is a full, clear, and exact description thereof.

10 This invention relates to amusement devices, and more particularly to what are commonly termed "teeters".

15 The primary object of the present invention is to provide a device of the foregoing character, which may be operated by a single person, instead of the customary two required to balance devices of this character.

20 A further object resides in the provision of means whereby the apparatus may be adjusted to persons of various height and weight.

25 A still further object resides in the specific construction of the counter-balancing means, whereby the same is rendered inoperative during a portion of the upward movement of the person using the apparatus.

With the above and other objects in view, which will appear as the description proceeds, the invention resides in the novel construction, combination and arrangement of parts, substantially as hereinafter described and more particularly defined by the appended claim, it being understood that such changes in the precise embodiment of the 35 herein disclosed invention may be made as come within the scope of the claim.

In the accompanying drawing is illustrated one complete example of the physical embodiment of the present invention constructed according to the best mode so far devised for the practical application of the principles thereof.

Figure 1 is a side elevation illustrating one form in which the invention may be designed, and

Figure 2 is a plan view, partly in section, as indicated on the line 2—2 of Figure 1.

Referring now more particularly to the accompanying drawings, wherein the present invention is designed to be portable, the same comprises a base 1 having secured thereto a standard 2 composed of a pair of upright members 3 and the brace members 4, both of which are slightly spaced apart for the reception of the horizontal beam 5.

The beam 5 is supported upon a fulcrum 6 comprising a bolt carried by the uprights 3. For the purpose of adjustment, that is to permit raising and lowering the beam 5 for persons of various heights, the uprights 3 are provided with a plurality of vertically spaced holes 7, for the reception of the fulcrum 6. The beam 5 is supported on the fulcrum by means of the spaced notches 8, which may be formed in a casting secured to the bottom, as shown, or formed in the beam itself. These notches permit longitudinal adjustment to the beam 5 to compensate for persons of different weight, thereby eliminating the necessity of adjusting the counter-balancing means to be later described.

The free end of the beam 5 is provided with a seat 9, of any conventional structure, and positioned on the beam directly in front of the seat, is an upright member 10, which may be of any figurative shape, such as that illustrated in the drawing, or plain. This upright serves to carry a pair of handles 11, which are within convenient reach of the operator's seat.

The opposite end of the beam 5 has secured thereto a bracket 12, provided with an upwardly inclined loop portion 3, in which is slidably secured one end of the counter-balancing spring 14, the other end of which is anchored to the base 1, where the same is employed. However, in instances where the device is permanently set up, it will be readily appreciated that the standards can be secured directly to the floor, in which instance the spring 14 would likewise be anchored to the floor.

From the foregoing description it will be seen that in the operation of the device 95 the spring 14 will serve as a counter balance for the person positioned upon the free end of the beam 5, and will assist in his upward movement to that point where the beam 5 is approximately horizontal. 100 Further upward movement of the operator, brought about through his own effort, will cause the counter-balanced end of the beam to travel downwardly, during which movement the end of the spring 14 retained within the loop 13 will travel rearwardly within the loop, thus rendering the spring inoperative during this portion of the downward stroke of the counter-balanced end of the beam, which prevents buckling of the 110

spring and a tendency to force this end of the beam upwardly with corresponding upward movement of the occupant.

To assist the counter-balance spring 14 in cushioning the downward movement of the operator, the free end of the beam 5 has secured thereto a bumper spring 15 which engages the base or floor at the limit of the downward movement of the beam.

10 It is also obvious that the bumper spring 15 will assist the counter-balance spring 14 in the initial upward movement of the free end of the beam.

From the foregoing, it will be seen that a 15 very simple and compact apparatus has been provided, which will readily permit of use by a single person, and which may be easily and quickly adjusted for height and weight.

I claim:—

A device of the character described, comprising, a base, a standard carried by said base, a fulcrum carried by the standard, a beam mounted on said fulcrum and provided with an occupant seat at one end, an upright secured on the beam in front of said seat and provided with handles, an upwardly inclined loop carried by the opposite end of said beam, a counter-balance spring having one end anchored to said base and the other end slidably secured within said loop, and means for cushioning the free end of said beam. 20 25 30 35

In testimony that I claim the foregoing I have hereunto set my hand at Kenosha, in the county of Kenosha and State of Wisconsin.

CHARLES KOCHER.
